UNITED STATES PATENT OFFICE

2,108,370

HIGHWAY MARKER

Otto Ernst, Larchmont, N. Y.

Application April 16, 1936, Serial No. 74,763

1 Claim. (Cl. 88—79)

My invention relates to highway markers, and more particularly to a marker which may be positioned at suitable intervals to indicate, by reflected light from an oncoming car, a curvature in the highway, the curbing of the highway, or otherwise apprise the motorists of some similar condition of the roadway, and it consists in the constructions, arrangements and combinations herein described and claimed.

10 It is a principal object of the invention to provide a marker wherein a full 360 degrees of reflecting surface is made available, thus insuring reflection of light from on-coming cars, at any angle.

15 It is a further object of the invention to provide a marker in which the reflecting surface thereof is fully protected against the weather, thereby insuring the production of a marker which is susceptible to long use and of a practical character, yet economical in manufacture.

Additional objects, advantages and features of invention will be apparent from the following description considered in conjunction with the accompanying drawing, wherein

25 Figure 1 is a perspective view illustrating one use of the marker.

Figure 2 is a cross sectional view through a roadway illustrating the mounting of the marker.

Figure 3 is a vertical sectional view through the 30 marker.

Figure 4 is a cross sectional view thereof.

Figure 5 is a vertical sectional view through a modified form of the marker.

Attention is first invited to Figure 1, wherein 35 the markers 10 are shown mounted at spaced points along a highway 11 to indicate the curb line 12. Obviously, since the markers 10 are spaced along the curb, any curvature in the highway will be indicated to motorists due to reflection of light from the headlights of an on-coming car, and if the markers are spaced at short intervals, especially at curves, a lighted guideway is produced, so that a true representation of the curve is impressed upon the driver of the vehicle.

40 In Figures 2, 3, and 4 there is shown a preferred form of the marker, and comprises a hollow body 13 of glass, which may be clear or colored and preferably polished. The body 13 includes a base 14 having an annular groove 15 therearound, which, as may be seen from Figure 2 functions as an anchorage when embedded in the soil at the side of the road. The body 13 immediately above the groove 15 is of tapering formation, thus forming the cone 16.

45 The inner face of the cone 16 is formed with a plurality of flutes 17 extending from a point above

the base to the apex of the cone and throughout the circumferential area thereof. The entire inner face of the cone including the flutes, is coated with any approved reflecting material and in use, it will be apparent that lights from on-coming 5 vehicles will strike the markers and by the arrangement of the flutes, no matter at what angle the light may be directed thereagainst, the light will be reflected back to the motorist.

In Figure 5, a modified form of marker is 10 shown, in which the body 18 has a semi-elliptical shape, the inner surface of which has flutes 19, conforming to the shape of the body and extending longitudinally thereof. The flutes and inner surface is silvered as in the first instance. The base of the body 18 is open and provided with a rabbet 20, within which a disk 21 is seated and sealed. The disk is centrally apertured as at 22, through which a standard 23 may pass, the upper end of the standard being engaged in a seat 24. 20 The standard 23 is sealed in the aperture of the disk in any approved manner, so as to exclude moisture, etc. This latter form of marker will be found highly efficient where it is necessary to place a marker in snow drifts or other obstructions which might tend to confuse a motorist, and therefore the shaft 23 will be of a length to permit burial of the lower end within a drift for support of the marker at a proper elevation above the drift.

25 In both forms of the device, it will be noted that the reflecting surfaces of the marker are completely sealed against air and moisture, thereby insuring long lasting quality of the reflecting coating.

30 Obviously the fluting may have various shapes, and one variation, is the provision of semi-spherical members upon the inner surface of the body member.

While I have shown and described certain preferred forms of the marker, this is by way of illustration only, and I consider as my own, all such modifications as fairly fall within the scope of the appended claim.

35 I claim:

40 A highway marker comprising a hollow transparent body member having an open end, a rabbet formed therearound, a disk seated within the rabbet and sealed therein, said disk having an aperture therethrough, a standard engaged through 50 the aperture and sealed therein, one end of the standard engaging the interior of the body member for support thereof, said body member having projections upon the interior thereof, and a reflecting material fixed to the interior surface 55 and the projections.

45 OTTO ERNST.
